JOHN DE GLORIA AND HARRY C. SCHROEDER, OF OAKLAND, CALIFORNIA

BUMPER ELEMENT FOR SAFETY ZONES

Application filed April 4, 1929. Serial No. 352,374.

The invention is for a barrier for street car loading platforms and safety zones which are placed in the street and usually in parallelism with the rails of a street car track and is for the purpose of preventing the driving of automobiles and the like over the platform.

The primary object of the invention is to provide a barrier having a cushioning face for receiving the shock of an automobile or the like colliding therewith.

A further object of the invention is to provide such a device that will be sightly and have means for readily detecting the location of the platform in the dark.

Other objects and advantages of the invention will readily appear as the following specification thereof proceeds, taken in conjunction with the accompanying drawings, in which:

Figure 1 is a plan view of street car loading platforms showing the barrier located at their respective ends.

Figure 2 is a side elevation on an enlarged scale of one end of one of the loading platforms showing the barrier secured thereto with a part of the platform broken away.

Figure 3 is a top plan view of Figure 2.

Referring to the drawings, reference character 10 indicates street car loading platforms of the usual type lying in parallelism with tracks 11 of a street railway. The loading platforms may be constructed of wood, concrete, or any suitable material and have at their outer ends pillars 12 extending upwardly therefrom for forming barriers to prevent the driving of automobiles over the loading platforms and may be provided with spot lights 13. Cushioning buffers 14 which may be composed of any yielding resilient material such as waste, straw, excelsior or other suitable material are secured to the outer faces of pillars 12 in any suitable manner, preferably by bands 15 having their ends secured to the pillar 12 as at 16. Depression 17 is preferably formed in the roadway for the reception therein of the lower end of the cushioning buffers 14 for the more definite securing of the buffer 14 in relation to the pillar 12, thereby avoiding the lateral

shifting of the buffer with relation to the pillar 12 when receiving the shock of an automobile colliding therewith.

Buffer 14 may be provided with a cover 18 of any suitable material in the interest of making the device more sightly.

Having thus explained the nature of the invention and described an operative manner of constructing and using the same, although without attempting to set forth all of the forms in which it may be made or all the forms of its use, what is claimed is:

1. An approach for passenger loading platforms, in combination with a standard; a U shaped metal member adapted to slidably engage the sides of said standard, said U shaped member being filled with resilient material.

2. An approach buffer for passenger loading platforms, in combination with a standard; a U shaped metal housing adapted to slidably engage said standard, retaining means for said housing, and, a resilient filler material for said housing.

3. An approach buffer for passenger loading platforms comprising a standard, a U shaped rigid housing extending forwardly thereof and slidably thereon, said housing being filled with resilient material coating between said standard and said housing.

In testimony whereof we have affixed our signatures.

JOHN DE GLORIA.
HARRY C. SCHROEDER.
